UNITED STATES PATENT OFFICE.

FREDERICK W. DILL AND JOHN R. HILL, OF LINCOLN, KANSAS.

CROSS-LINE BUCKLE.

No. 868,161.

Specification of Letters Patent.

Patented Oct. 15, 1907.

Application filed April 2, 1907. Serial No. 365,944.

To all whom it may concern:

Be it known that we, FREDERICK W. DILL and JOHN R. HILL, citizens of the United States, residing at Lincoln, in the county of Lincoln and State of Kansas, have invented certain new and useful Improvements in Cross-Line Buckles, of which the following is a specification.

This invention has for its object an improved construction of cross line buckle possessing novel and useful features that will be hereinafter specifically described and particularly pointed out in the appended claims.

For a full understanding of the invention and the merits thereof and also to acquire a knowledge of the details of construction of the means for effecting the result, reference is to be had to the following description and accompanying drawings, in which:

Figure 1 is a perspective view of our improved cross line buckle; Fig. 2 is a longitudinal sectional view thereof; and, Fig. 3 is a detail perspective view of the auxiliary tongue.

Corresponding and like parts are referred to in the following description and indicated in all the views of the drawings by the same reference characters.

The frame 1 of our improved cross line buckle is provided with an intermediate cross bar 2 to which the main tongue 3 is pivoted, and with end cross bars 4 and 5.

To one of the end bars (4) an auxiliary tongue 6 is pivoted, said tongue being provided with a plate-like base portion 7 which is formed with an opening 8 and two curled lugs 9 on opposite sides of said opening, said lugs encircling the cross bar so as to pivot the auxiliary tongue thereto. The opening of the said auxiliary tongue 6 is adapted to receive the outer end of the main tongue 3 so as to hold it locked against the cross bar 4 between the lugs 9, while the free end of the auxiliary tongue 6 is adapted for engagement with the opposite cross bar 5.

Of the straps that are secured to the buckle hereinbefore described, the strap A represents the outer check, the strap B the cross line, and C the hand portion of said line, said line being secured to the frame 1 by means of the tongue 3 in the usual manner. The outside check A is provided with two openings 10 adapted to receive the auxiliary tongue 6.

From the foregoing description in connection with the accompanying drawing, it will be seen that in operative position, the base of the auxiliary tongue 6

constitutes a locking plate for the main tongue 3. Whenever it is desired to use the outside check A as a hitching strap, it is obvious that this may be done by merely detaching said strap from the auxiliary tongue without interfering in any wise with the cross line B. As the main tongue 3 is locked down against the cross bar 4, it will not catch on any other projecting parts of the harness or on fly nets, nor catch in the horse's tail, and it is obvious that the invention can be used on lines, hip-straps, back-straps, and other portions of harness.

It is evident that we have produced a very cheap, durable and efficient construction of detachable check buckle embodying an arrangement of parts whereby the main tongue is locked in operative position and in which the outside check may be securely held in place as long as desired and very readily detached whenever it is desired to use it as a hitching strap or the like.

While the accompanying drawing illustrates our improved cross line buckle as arranged for a two horse team, it is manifest that the buckle is applicable to teams of three, four, or more horses. To add the third horse, it is only necessary to put an extra check in the buckle, punch one hole in the end of the check and attach to the main tongue (or short tongue). For a four horse team, another check may be added to the main tongue.

Having thus described the invention, what is claimed as new is:

1. As an improved article of manufacture, the herein described buckle, comprising a frame embodying end bars, an intermediate cross bar, a main tongue pivotally connected to said intermediate cross bar, and an auxiliary tongue pivotally connected to one of the end cross bars and adapted for locking engagement with the main tongue. 80
2. As an improved article of manufacture, the herein described harness buckle, comprising a frame embodying end cross bars and an intermediate cross bar, a main tongue attached to said last named bar and adapted to engage one of the end cross bars with its free end, an auxiliary tongue pivotally connected to said end cross bar and provided with an opening through which the outer end of the main tongue is adapted to project, and an auxiliary tongue adapted for locking the main tongue in operative position. 90

In testimony whereof we affix our signature in presence of two witnesses.

FREDERICK W. DILL. [L. S.]
JOHN R. HILL. [L. S.]
